HIS ATTORNEY

UNITED STATES PATENT OFFICE.

RAYMOND H. SMICKLE, OF BELVIDERE, NEW JERSEY, ASSIGNOR TO INGERSOLL-RAND COMPANY, OF JERSEY CITY, NEW JERSEY, A CORPORATION OF NEW JERSEY.

RETAINER FOR ROCK-DRILL STEELS.

Application filed May 20, 1924. Serial No. 714,571.

To all whom it may concern:

Be it known that I, RAYMOND H. SMICKLE, a citizen of the United States, and a resident of Belvidere, county of Warren, and State 5 of New Jersey, have invented a certain Retainer for Rock-Drill Steels, of which the following is a specification, accompanied by drawings.

This invention relates to rock drill steel 10 retainers, but more particularly to that type which includes a bale pivotally mounted on the front head of the rock drill which is adapted to loosely embrace the steel. Drill 15 steels used in combination with this type of steel retainer are provided with collars on the shank which in combination with the bale, form an obstruction to the withdrawal of the steel from the drill chuck.

In many steel retainers of this type, the 20 bale is adapted to swing on flat sided pivots or trunnions mounted on the front head of the drill, the pivotal aperture in the bale being likewise flat sided so that the bale is held positively in the steel retaining position. 25 Springs are usually provided for pressing the bearing of the bale into engagement with the pivot through the medium of rods or plungers suitably held in place on the bale. When nuts are provided on the 30 plungers to hold them on the bale or to tension the spring, it is somewhat inconvenient to remove the springs and bale from the pivot.

One object of this invention is to enable 35 a steel retainer to be readily removed and replaced on the rock drill. Other objects and advantages will be in part obvious and in part pointed out hereinafter.

A preferred embodiment of the invention 40 is described hereinafter in conjunction with the accompanying drawings, in which—

Figure 1 is a plan view of the front end 45 of a rock drill with the steel retainer in position holding the steel within the chuck,

Figure 2 is a side elevation showing the 50 steel retainer in its steel engaging position,

Figure 3 is a side elevation showing the 55 steel retainer swung to its position for releasing the steel,

Figure 4 is a perspective view showing the 60 pivoted bearing, plungers, and plunger retainer apart from the steel retainer, and

Figure 5 is a section along the line 5—5

through the rearward extension of the bale and shows the manner in which the plunger 55 is held in position by the plunger retainer.

The drawings illustrate the steel retainer mounted on the forward end of a typical rock drill, only so much of the drill being illustrated as is useful for purposes of this 60 description. The drill as shown includes a front head A, a cylinder B and a front cylinder bushing C, these parts being held together by means of through bolts D provided with front head springs E to absorb 65 the shock of the hammer piston (not shown) striking against the front head when the steel F is removed.

The front head A is provided with a pair of trunnions or pivots G upon which is 70 pivotally supported the steel retainer which in accordance with the practice of this invention comprises a bale H having squared notches J within which the trunnions G are adapted to fit. The forward end of the bale 75 H is bent as at K to fit around and embrace the steel F. The rearward end of the bale H is provided with extensions L terminating in forked ends O (Figure 5).

Bearings P for the trunnions G are slidably held in position in the notch J, said notch being cut away as at Q to receive the bearing P which is also supported partly by the rearward extension L. The trunnions G are held tightly between the bearings P 80 and the notch J of the bale H by means of a spring R bearing against a plunger S having a head T. The plunger S loosely engages the bearing P as by means of a reduced portion U on the forward face of the head T 85 which fits into an aperture V cut in the back of the bearing P. Thus, while the plunger S is held in engagement with the bearing P when in place on the rearward extension L of the bale H the plunger and the bearing 90 may be readily removed from such engagement by depressing the spring R. In assembling the spring R, plunger S and the bearing P, the bearing is first placed in the notch J next to the trunnions G, and thereafter the reduced portion U of the plunger S is engaged through the rear end of the bearing and the rearward end of the plunger S is then inserted in the forked end O of the extension L, the spring R having previously 95 been placed on the shank of the plunger

100
105

S. In order to hold the plunger S in position in the forked end O the latter is notched and recessed so as to engage with a retaining member or washer W slidably mounted on the shank of the plunger S. The spring R is adapted to bear against the head T of the plunger S and the retaining washer W. In order to remove the plunger it is merely necessary to depress the retaining washer W 10 to disengage the notch in the fork O and then to pry the assembly away from the rearward extension L. In replacing the assembly, pressure on the side of the plunger S forces the washer W into position, the forked 15 end O being beveled as at X to allow the washer W to slide into place.

Preferably, the trunnions G are provided with a flat side Y which engages the bottom of the notch J in the steel retaining position 20 of the steel retainer as shown in Figures 1 and 2, the cooperation of these flat surfaces in addition to the pressure of the spring R prevents the steel retainer from jarring out of its steel retaining position. 25 However, the bale H may be rotated on the trunnions G by slight pressure when it is desired to remove the steel F from the front head A.

The above described steel holder is adapted 30 to be used with the usual form of steel, either hexagonal or round or any desired form, usually having a collar Z formed on the shank of the steel F which is too large to pass by the bent end K of the bale.

35 I claim:

1. A rock drill steel retainer comprising a pivoted bale having an extension at its rearward end, a bearing member mounted on said extension and adapted to engage a pivot for said bale, means for holding said bearing into engagement with said pivot, and means for supporting said means on

said extension including a spring pressed member engaging said extension.

2. A rock drill steel retainer comprising a pivoted bale having an extension at its rearward end, a bearing member mounted on said extension and adapted to engage a pivot for said bale, a spring pressed plunger for holding said bearing member into engagement with said pivot, and a spring pressed member engaging said extension to support said plunger on said extension.

3. A rock drill steel retainer comprising a pivoted bale having an extension at its rearward end, a bearing member mounted on said extension and adapted to engage a pivot for said bale, a plunger loosely engaging said bearing member, a retaining member slidable on said plunger, and a spring about 60 said plunger adapted to press against said retaining member and said plunger to maintain the bearing member in engagement with said pivot, said extension having a forked end to receive said plunger and notched to 65 engage said retaining member.

4. A rock drill steel retainer comprising a bale provided with a flat sided notch adapted to engage a flat sided pivot and having a rearward extension forked at its end, a bearing member for said pivot slidable in said notch and supported by said extension, a plunger loosely engaging said member and insertable in the forked end of said extension, a retaining member slidable on said plunger and engageable with the forked end of the extension, and a spring bearing 70 against said retaining member and the plunger to hold the bearing in engagement with said pivot.

In testimony whereof I have signed this specification.

RAYMOND H. SMICKLE.
